UNITED STATES PATENT OFFICE.

HULSER M. GALE, OF SYRACUSE, NEW YORK.

DESIGN FOR A CARTON-HOLDER.

No. 39,545.

Specification for Design.

Patented Sept. 15, 1908.

Application filed April 30, 1908. Serial No. 430,240. Term of patent 3½ years.

To all whom it may concern:

Be it known that I, HULSER M. GALE, of Syracuse, in the county of Onondaga, in the State of New York, have invented a new, original, and ornamental Design for Carton-Holders, of which the following, taken in connection with the accompanying drawings, is a full, clear, and exact description.

The figure is an isometric view of the carton holder showing my new design.

The salient features of this design consists in the rectangular form of the holder; the substantially rectangular openings in the

sides and ends; the beaded fillets at the corners of the openings; the scroll handles extending centrally across the end openings from top to bottom and the rounding feet at the four corners of the bottom.

I claim:

The ornamental design for a carton holder as shown and described.

HULSER M. GALE.
